UNITED STATES PATENT OFFICE.

ANTHONY GRAMOWSKI, OF ST. JOSEPH, MISSOURI.

CHIMNEY AND PIPE CLEANER.

Application filed March 29, 1922. Serial No. 547,828.

To all whom it may concern:

Be it known that I, ANTHONY GRAMOWSKI, a citizen of the United States, residing at St. Joseph, in the county of Buchanan, State of Missouri, have invented a new and useful Chimney and Pipe Cleaner; and I do hereby declare the following to be a full, clear, and exact description of the invention, such as will enable others skilled in the art to which it appertains to make and use the same.

The invention relates to chimney and pipe cleaners and has for its object to provide a device of this character comprising substantially cylindrically shaped sleeves, the ends 15 of which are overlapped, the outer sleeve being provided with brushing elements adapted to engage the inner periphery of a chimney or pipe for dislodging soot or the like. Also to provide turn buckle means 20 for expanding and contracting the device, thereby allowing the same to be adjusted for different size chimneys or pipes.

A further object is to provide a weight suspended from the lower turn buckle for 25 forming means for pulling the device downwardly in a chimney or the like and to provide cable means connected to the upper turn buckle forming means whereby the device may be pulled upwardly in a chimney or 30 the like.

With the above and other objects in view the invention resides in the combination and arrangement of parts as hereinafter set forth, shown in the drawings, described and 35 claimed, it being understood that changes in the precise embodiment of the invention may be made within the scope of what is claimed without departing from the spirit of the invention.

40 In the drawings:—

Figure 1 is a vertical sectional view through the device.

Figure 2 is a top plan view.

45 Figure 3 is a vertical sectional view through a modified form of cleaner, showing the same in a stove pipe and the handle thereof extending through a plate.

Referring to the drawings, the numeral 1 designates a cylindrically shaped member 50 having its ends overlapped as at 2 thereby allowing the cylindrical member to be expanded and contracted by means of the turn buckles 3 which are secured at 4 in opposite walls of the cylindrical member 1. It will be seen that the turn buckle 3 when revolved on the threaded rods 5 will cause the cylin-

drical member 1 to either be expanded or contracted according to the direction of rotation of the turn buckles 3, thereby allowing the device to be adjusted for use in 60 connection with different sizes of chimneys and pipes. Frictionally engaging the outer periphery 6 of the cylindrical member 1 is a contracting sleeve 7, which sleeve carries radially disposed tufts of wire 8, which engage 65 the wall of the chimney or pipe and dislodge soot and the like.

Suspended from collars 9 carried by the lower threaded rods 5 by means of wires 10 which are connected at 11 to the collars 9 70 is a weight 12, which is axially disposed in relation to the cylindrical member 1 and forms means in connection with the weight of the device for pulling the device downwardly through a chimney or pipe. The 75 device is moved upwardly by means of a cable 13 which is connected to collars 14 carried by the upper threaded rod 5 through the medium of wires 15. It will be seen that the device may be reciprocated in a chimney 80 or pipe by allowing the weight 12 to pull the device downwardly and the operator pulling the device upwardly by means of the cable 13.

Referring to Figure 3 wherein a modified 85 form is shown, the brushing element 16 is disposed in a stove pipe 17 and is carried by a handle 18 by means of which handle the brushing handle may be reciprocated for cleaning the interior wall of the stove pipe. 90 It has been found during a stove pipe cleaning operation that soot as it is dislodged by a reciprocating brush is forced outwardly from one end of the pipe incident to the pumping action. To obviate this difficulty, 95 a disc shaped member 19 is provided for engaging in the end of the pipe and through an aperture 20 in which disc the handle 18 passes. The disc 19 is provided with a handle 21, whereby it may be easily handled and 100 held during the pipe cleaning operation.

From the above it will be seen that chimney and pipe cleaner is provided, which device is simple in construction, may be adjusted to various diameters of chimneys or 105 pipes and may be easily manufactured.

The invention having been set forth what is claimed as new and useful is:—

1. A chimney cleaning device comprising an expansible cylindrical member, parallel 110 disposed turn buckles connecting the opposite walls of said cylindrical member and

forming means whereby it may be expanded or contracted, and a contractible brush carrying sleeve surrounding the cylindrical member and engaging the outer periphery thereof.

2. A chimney cleaning device comprising a split cylindrical member, turn buckles disposed within the cylindrical member and connected to the opposite walls thereof and forming means whereby the cylindrical member may be expanded or contracted, a contracting sleeve surrounding the cylindrical member, brushing elements carried by said contracting sleeve, a weight suspended from one of the turn buckles and axially disposed in relation to the cylindrical member and forming means for pulling the device downwardly and means connected to the other turn buckle and forming means whereby the device may be pulled upwardly.

3. A chimney cleaning device comprising a split expansible sleeve, turn buckles for expanding and contracting said sleeve, a split contractible brush carrying sleeve frictionally engaging the periphery of the first mentioned sleeve, turn buckles for expanding and contracting the first mentioned sleeve and means whereby the device may be reciprocated in a chimney, said means comprising a weight suspended from the lower end of the device and a cable connected to the upper end of the device. 25 30

In testimony whereof I have signed my name to this specification in the presence of two subscribing witnesses.

TONEY GRAMOWSKI.
